FLASHLIGHT

Orville T. Wood, Clinton, Mass., assignor to Blake Manufacturing Corporation, Clinton, Mass., a corporation of Massachusetts

Application May 6, 1938, Serial No. 206,326

4 Claims. (Cl. 240—10.66)

This invention relates to flashlights and more particularly to flashlights commonly known as pen lights of a size only slightly larger, relatively speaking, than a fountain pen and so constructed and arranged as adapted to be carried in the pocket.

One object of the present invention is a flashlight of the character described in which the lamp is removably carried in an end closure member at one end of a tubular flashlight casing containing the battery.

Another object of the invention is to provide a combined lamp supporting member and reflector removable as a unit.

Another object of the invention resides in the instrumentalities by which the circuit between the lamp and battery may be completed.

The invention also seeks a flashlight of the character described which is practical from the standpoint of ease and cheapness of manufacture and simplicity and durability in use.

These and other objects of the invention and the means for their attainment will be more apparent from the following detailed description, taken in connection with the accompanying drawings illustrating various embodiments by which the invention may be realized and in which:

Figure 1 is a view in side elevation showing the flashlight of this invention;

Figure 2 is a longitudinal sectional view of one form taken by the invention, showing details of its construction;

Figure 2a is a fragmentary view looking in the direction of the arrows 2a—2a in Figure 2, parts being removed to show details of construction;

Figure 3 is a view showing the upper end of a flashlight, in elevation, embodying one modification of the invention;

Figure 4 is a longitudinal sectional view of the flashlight of Figure 3 showing details of construction;

Figure 5 is a transverse sectional view, taken in the plane indicated by the line 5—5 of Figure 4, and looking in the direction of the arrows;

Figure 6 is a fragmentary view on an enlarged scale, and in elevation, showing a modified form of the invention;

Figure 7 is a longitudinal sectional view of the circuit closing device of Figure 6;

Figure 8 is a view of the flashlight casing of Figure 7, exterior parts being removed in the interest of clearness; and

Figure 9 is a sectional view showing still another modification of the invention.

While the invention has been illustrated and

described as particularly applicable to a so-called pen light, it will be obvious as the description proceeds that many features thereof are equally applicable to any flashlight or electric hand lantern.

Referring first to Figures 1 and 2, the flashlight there shown comprises a tubular, and conveniently cylindrical, casing 10 formed with threads rolled therein as at 12, 14 at each end. Both ends of the casing are open. The casing may, if desired, be provided with the usual type of clip 15 to removably retain the flashlight in the pocket.

The bottom cap of the flashlight may take the form of a generally cup-shaped member 16, 20 of an outer diameter, as at 16, substantially equal to the outer diameter of the tubular casing 10. Above the peripheral surface 16 the wall of the cup-shaped bottom cap is of reduced diameter and formed with threads, as at 18, whereby the threaded end 18 may be telescoped within the threaded end 12 of the flashlight casing until the respective parts 16 and 18 are in abutting relation as shown in Figure 2. An area of the bottom of the bottom cap inwardly of the peripheral surface 16 is conveniently depressed as shown at 20 whereby the part 16 forms a circumferential rib, which may conveniently be knurled, as shown at 17, for convenience in manipulation and which defines a groove on the inner surface to receive and retain a battery positioning spring 21 shown as a coil spring, the upper coil of which is adapted to engage and make electrical connection with the zinc cup terminal of the battery 22 and urge the battery upwardly toward the terminal of the lamp at the upper end.

The lamp is conveniently carried in a cup-shaped member 23, 26 which is of a diameter such as to be received within the cylindrical casing 10 and is formed with threads 24 for threaded engagement with the inside surface of the threads 14. In the bottom 23 of this cup-shaped member 23, 26 and centrally thereof, there is formed an aperture 25 the rim of which is distorted and interrupted to form, in effect, a thread adapted to receive the threaded base 29 of a lamp 27 and make electrical connection with the shell terminal of the lamp. Inward movement of the lamp support 23, 26 is preferably limited, as by a lip or flange 26 on the upper edge of the cup 24 adapted to engage the rim of the casing as a stop.

The lamp is held in the flashlight casing or lamp socket support therein or at least is protected against injury by a closure member 30, 36 formed with a cylindrical threaded portion 30

adapted to be screwed down into the threaded wall 24 of the cup-shaped lamp support until a bead 31 formed on the closure member abuts the rim 26 of the lamp socket support. Above the bead 31, the enclosure is frusto-conical in shape as shown at 33 and in its upper end is concave or dish shaped as shown at 34 and formed with a central aperture 36 to engage, if desired, the globe of the lamp 27, 28 and serve as a light transmitting aperture. The surrounding concave 10 wall 34 serves as a reflector.

Normally, it is contemplated that the circuit be completed, in the flashlight of this invention, by electrical connection between the central terminal 38 of the battery 22 and the central terminal 40 of the lamp. Normally, the terminal 38 is held away from the lamp terminal 40 by a reciprocable member 49 which is adapted to move the battery downwardly to compress the spring 21 but which member may be moved upwardly until it engages the lamp terminal 40, the battery following the member under the influence of the spring 21. Generally this member comprises a rodlike bar 49 the ends of which are disposed in generally U-shaped slots 42, 44, 50 formed in the casing 10. Intermediate its ends, the bar carries a conductive tube 43 insulated from the bar by the insulatory sleeve 45 encircling the bar and within the tube 43. The conductive tube 43 is adapted to engage the 20 central terminal 40 of the lamp and is normally in contact with the battery terminal 38. The contact means 43 is insulated from the conductive battery containing casing 10 by the insulatory sleeve 45 so that short circuit between 35 the central terminal 38 of the battery and the casing 10 is not possible. Outwardly of the casing, there is mounted, in this modification, a rotatable sleeve 47 whereof a portion, such as the knurled annulus 48, may be secured to the 40 ends of the bar 49, the ends 49 passing through slots 50 in the casing 10 whereby rotation of the sleeve 47, 48 will enable the bar ends 49 to be moved up in one of the ends 42 of the slot 50 until the contact 43 is in engagement with the central terminal 40 of the lamp, all under the influence of the battery spring 21. Thus electrical connection is made from the battery terminal 38 through the contact means 42 and the central terminal of the lamp 40, while the circuit is completed from the lamp shell 29 and cup-shaped lamp support 23, 26 through the conductive battery containing casing 10, the battery positioning spring 21 to the zinc cup terminal of the battery 22, it being understood that the battery is enclosed in the usual insulating sleeve, such as a fiber tube, whereby the zinc cup terminal of the battery is insulated from the conductive casing 10. In open circuit position, the ends of bar 49 are disposed in an intermediate and shorter slot portion 44 when the conductive member 43 is held away from lamp contact 40.

The modification illustrated in Figures 3, 4 and 5 differs from the modification of Figures 1 and 2 in the form taken by the circuit closing element. Like parts in these figures are given corresponding reference characters. In this modification, Figure 4, the transverse movable wall corresponding in function to the wall 43, 70 is illustrated as a cup-shaped member 51, 54 whereof the wall is indicated at 51 and the bottom at 52. The bottom 52 is provided with a central aperture 54, the diameter of which is such that the shank of the rivet or eyelet 56 75

may pass therethrough with clearance so as to be out of electrical connection therewith. Above and below the bottom 52 are insulatory washers 57, 58 clamped in position by the eyelet 56, the heads 46 and 53 of the eyelet or rivet serving as the contact means for the battery terminal 38 and the lamp terminal 40, as will be understood. The wall 10 of the battery containing casing is formed with an inwardly pressed groove for convenience although it will be obvious that such is not necessary to the operative character of the invention. The inward bead 55 serves as a bearing surface for the reciprocable wall. Covering the peripheral groove 55 is a sleeve 59 and, conveniently, in diametrically opposite portions of the part 55, there are formed curved slots 60 through each of which a rivet or the like 62 may pass. The rivet is illustrated as a split rivet carried in the sleeve 59 and, as shown in Figure 5, passes through the slot 60 in the wall portion 55 and through the wall 51 of the cup-shaped circuit closing member where it is fixed in position as by bending over each furcation 63 as shown. The slot 60 may be so disposed that one extremity thereof is higher than the other as shown in dotted lines in Figure 3 and as the sleeve 59 is rotated, the rivet 62 is caused to follow the slot and move upwardly to bring the eyelet 56 into electrical connection with the lamp terminal 40 thus completing the connection because the battery positioning spring 21 causes the battery 22 to follow the wall as in the previously described modification.

The flashlight of Figures 6, 7 and 8 is in the main, similar to that previously discussed and corresponding parts are given like reference characters. In this instance, however, the movable wall comprises a pair of insulating discs 65 spaced as by a suitable spacing element 67 and clamped together as by the eyelet 69. One overturned edge 70 of the eyelet serves as the contact with the terminal 38 of the battery. The other turned over edge 71 serves as the contact means with the lamp terminal 40. The wall of the casing in this modification is again formed with a curved slot 73, 75 which may, if desired, take the form of diverging upwardly extending portions, a longer slot 73 and a shorter slot 75 (as shown in Figure 8). A sleeve 77 on the outside of the casing 10 is formed at its bottom end with a bead 78 and pins 79 of some convenient size are secured in the sleeve 77 and enter the space between the insulating washers 85. If desired, for appearance sake, the pins may be hidden from view and retained against displacement by an external offset sleeve 80 secured permanently on the sleeve 77. When the pins 79 are in the slot portion 75, the contact 69, 70 is held away from the lamp. When the pins 79 are in the end of the slot portion 73, the contact 69, 71 engages the lamp terminal 40. The operation of the flashlight in this modification is the same as described hereinbefore.

A simple form of the invention is illustrated in Figure 9. The battery containing casing 10 receives, at one end, a cup-shaped bottom cap 82 the wall of which is threaded as before to mesh with a simple single helical groove 83 rolled in the casing wall. Instead of the positioning wall of the previously described modifications, a simple sleeve 77, 78 similar to that described hereinbefore is adapted to turn and reciprocate on the casing 10. Inwardly directed pins 85 are carried in the sleeve and pass through slots similar to those shown at 73, 75 of Figure 8. The pins

are adapted to engage the rim of the battery 22. When the sleeve 11 is rotated so that the pin 85 lies in the slot portion 75, the battery has been moved downwardly to contract the spring 21 so that the terminal 38 is out of contact with the lamp terminal 40. When, however, the sleeve 11 is turned so that the pin lies in the upper end of the slot portion 73, the battery positioning spring 21 urges the battery upwardly to bring its terminal 38 into direct contact with the lamp terminal 40 to complete the circuit as before.

It will thus be seen that a flashlight has been provided which is extremely simple in construction, is pleasing in appearance and comprises a circuit closure which enables the circuit to be completed by or under the influence of the battery positioning spring without complicated switch mechanisms.

Various modifications will occur to those skilled in the art, in the composition, configuration and disposition of the component elements going to make up the invention as a whole as well as in the selection and/or combination of individual features to accomplish particular objects and no limitation is intended by the phraseology of the foregoing specification or illustrations in the accompanying drawings, except as indicated in the appended claims.

What is claimed is:

1. A flashlight comprising a tubular casing, lamp supporting means in the casing, a lamp supported thereby, a battery in the casing, battery positioning circuit closing means comprising an axially reciprocable member disposed intermediate the battery and the lamp base, contact means mounted on said member on opposite sides thereof comprising means adapted to make electrical contact with the lamp terminal on one side and means adapted to make electrical contact with the battery terminal on the other side and means permanently electrically connecting the respective contact means, a battery positioning spring normally urging the battery terminal toward the battery positioning circuit closing member and maintaining a terminal of said battery in electrical contact with a contact means on said circuit closing member and means to maintain the circuit closing member in a closed circuit position in electrical contact with the lamp terminal and in an open circuit position in spaced relation to the lamp terminal.

2. A flashlight comprising a tubular casing, lamp supporting means in the casing, a lamp supported thereby, a battery in the casing, battery positioning circuit closing means comprising an axially reciprocable member disposed intermediate the battery and the lamp base, contact means mounted on said member on opposite sides thereof comprising means adapted to make electrical contact with the lamp terminal on one side and means adapted to make electrical contact with the battery terminal on the other side

and means permanently electrically connecting the respective contact means, a battery positioning spring normally urging the battery terminal into contact with the battery positioning member 5 and urging a terminal of said battery into electrical contact with a contact means on said circuit closing member and means to maintain the circuit closing member in a closed circuit position in electrical contact with the lamp terminal 10 and in an open circuit position in spaced relation to the lamp terminal, said last named means comprising a pin carried with the member, said casing being formed with a generally circumferential slot to receive the pin, one end of said 15 slot being in advance, longitudinally, of the other end and means outwardly of the casing to manipulate the pin.

3. A flashlight comprising a tubular casing, lamp supporting means in the casing, a lamp supported thereby, a battery in the casing, battery positioning circuit closing means comprising an axially reciprocable member disposed intermediate the battery and the lamp base, contact means mounted on said member on opposite sides thereof comprising means adapted to make electrical contact with the lamp terminal on one side and means adapted to make electrical contact with the battery terminal on the other side and means permanently electrically connecting the respective contact means, a battery positioning spring normally urging the battery terminal toward the battery positioning circuit closing member and urging a terminal of said battery into electrical contact with a contact means on said circuit closing member and means to maintain the circuit closing member in closed circuit position in electrical contact with the terminal 30 and in an open circuit position in spaced relation to the lamp terminal, said last named means comprising at least one pin carried with the member, the casing being formed with a U-shaped slot for a pin whereof the arms extend toward the end of the casing containing the lamp and a shorter slot intermediate said arms.

4. A flashlight comprising a tubular casing, said casing being formed with generally circumferentially extending slots one end of each of which is in advance longitudinally of the other end of the slot, lamp supporting means in the casing, a lamp supported thereby, a battery in the casing, a battery positioning spring normally urging the battery terminal toward the lamp base and means to maintain the battery in circuit closed position in electrical connection with the lamp terminal and in open circuit position out of electrical connection with the lamp terminal comprising a sleeve longitudinally reciprocable and axially rotatable on the outside of the casing and means carried by the sleeve and passing through each slot and having a portion 45 engaging the battery.

ORVILLE T. WOOD.
